CLAIM

The ornamental design for a beverage bottle illuminator, as shown.

DESCRIPTION

FIG. 1 is a bottom view of the beverage bottle illuminator without a base cover attached.

FIG. 2 is a bottom view of the beverage bottle illuminator with the base cover attached.

FIG. 3 is a top view of the beverage bottle illuminator.

FIG. 4 is an isometric view of the beverage bottle illuminator without the base cover attached.

FIG. 5 is an isometric view of the beverage bottle illuminator with the base cover attached.

FIG. 6 is a front view of the beverage bottle illuminator.

FIG. 7 is a rear view of the beverage bottle illuminator.

FIG. 8 is a left side view of the beverage bottle illuminator.

FIG. 9 is a right side view of the beverage bottle illuminator.

FIG. 10 is an isometric view of the beverage bottle illuminator with the base cover attached and the illuminator attached to a beverage bottle. The beverage bottle is not claimed; and,

FIG. 11 is an isometric view of the beverage bottle illuminator attached to a beverage bottle showing the assembly parts of the illumination device and the base cover. The illumination device and the beverage bottle are not claimed.
